HYMAN AUGUSTINE WILDER, OF MILLVILLE, ASSIGNOR TO GEORGE L. SQUIER, OF BUFFALO, NEW YORK.

Letters Patent No. 96,752; dated November 9, 1869.

IMPROVED CENTRIFUGAL MACHINE FOR DRAINING SUGAR.

The Schedule referred to in these Letters Patent and making part of the same.

To all whom it may concern:

Be it known that I, HYMAN AUGUSTINE WILDER, of Millville, in the county of Orleans, and State of New York, have invented a new and useful Improvement in Centrifugal Machines for Draining Sugar; and I do hereby declare that the following is a full and exact description thereof, reference being had to the accompanying drawings, and to the letters of reference marked thereon.

The chief object of my invention is to secure a continuous feed and continuous discharge in a centrifugal machine for draining sugar, and thus prevent the waste of power, labor, and time, hitherto attending centrifugal machines, on account of the necessity of stopping the machine to charge and discharge the same.

My invention consists—

First, in making the revolving-basket with conical or flaring sides;

Secondly, in feeding or charging such basket at or near its smaller end;

Thirdly, in a revolving worm, screw, or spiral, producing a positive mechanical or automatic feed; and

Fourthly, in discharging the sugar from the machine by means of the centrifugal motion, and receiving the sugar in a separate receptacle.

In the accompanying drawings—

Figure 1 is a side view of my machine.

Figure 2 is a vertical section of the same.

In the construction of my new centrifugal machine for draining sugar, the frame A may be of the usual form, with an upright shaft, B, provided with a hand-pulley, C.

Attached to shaft B is a conical or flaring basket, D, made of perforated tin or of wire, the bottom E of the basket being made solid.

The mush is fed into this basket through a stationary hopper, F, which extends nearly to the bottom of the basket, and the shaft carries a screw or spiral G,

which pushes the mush down through the hopper, and thus prevents the possibility of clogging, and also produces a uniform feed.

Outside of the basket is a curb, H, to which is attached an inner hollow cylinder or directing-plate, I; and outside of the dripping-pan K is a receptacle, L, for the sugar as it falls over the edge of the basket.

By the above arrangement, it is not necessary to stop the machine, either to put in the sugar or to discharge the same. The mush may be fed continuously into the hopper F, and it descends into the basket, when the centrifugal motion drives the sugar gradually up the flaring sides of the basket, until it falls over the top, as indicated by the arrow in fig. 2.

I do not confine my invention to the vertical machine above described, as the shaft may be set horizontally; in that case, the mush might be fed into the small end of the basket; and I do not broadly claim the screw or spiral as heretofore used, yet I believe it is new as a means of feeding sugar or mush into the centrifugal drainer. The form and position of the receptacle L may be varied.

Having described my invention,

I claim—

1. The basket D, when made conical or with flaring sides, substantially in the manner and for the purposes set forth.

2. A hopper, so arranged as to feed the mush continuously to the bottom or near the bottom of the basket, substantially as set forth.

3. The spiral G, or its equivalent, for the purpose of securing a uniform feed, substantially as described.

4. In combination with the basket, a receptacle for receiving the sugar as it falls over the edge of the basket.

HYMAN AUGUSTINE WILDER.
